Inventor;

John Mueller,

UNITED STATES PATENT OFFICE.

JOHN MUELLER, OF ELMHURST, ILLINOIS.

SEESAW AND ROUNDABOUT.

No. 823,618.

Specification of Letters Patent.

Patented June 19, 1906.

Application filed October 18, 1905. Serial No. 283,299.

To all whom it may concern:

Be it known that I, JOHN MUELLER, a citizen of the United States of America, and a resident of Elmhurst, in the county of Du- 5 page and State of Illinois, have invented cer- tain new and useful Improvements in See- saws and Roundabouts, of which the follow- ing is a specification.

This invention relates to combined see- 10 saws and roundabouts; and its main object is to provide improved construction and ar- rangement of the various parts of the de- vices of this class.

I accomplish these objects by the device 15 shown in the accompanying drawings, in which—

Figure 1 is a top plan of a combined seesaw and roundabout constructed according to my invention, one arm of the beam being broken 20 away and the middle seat being removed. Fig. 2 is a longitudinal section of the same on the line 2 2 of Fig. 1. Fig. 3 is a transverse section of the same on the line 3 3 of Fig. 1. Fig. 4 is a section on the line 4 4 of Fig. 2.

25 The device shown consists of a beam 4, balanced and rotatably mounted on the top of an upright post 5. The post 5 is pointed at the lower end and is driven into the ground, being braced by means of plank or plate 6. 30 The plate 6 is provided with a central aperture which fits the largest diameter of the post 5, and said plate has portions extending in opposite directions and provided with apertures near their ends for receiving the stakes 7, 35 with which the plate 6 is pinned to the ground.

The beam 4 is formed of a pair of substan- tially parallel side bars 8, which are disposed on edge, being spaced apart and securely fastened together by means of through-bolts 9.

40 Both ends of the beam 4 are alike, one being broken away in the drawings. The spacers 10, which are near the middle of the length of the beam, are spaced apart from each other to provide a central aperture 11. The spacers 12 and 13 are somewhat thinner than the

45 spacers 10 for reasons which will appear hereinafter. The opposed faces of the side bars 8 are provided with longitudinal grooves 14, extending between the spacers 12 and 13 at each end of the beam. A block 15 is mounted

50 between the side bars 8 at each end of the beam and has a pair of horizontal pins 16 ex- tending transversely through the same near each end and projecting beyond each of the 55 side faces of the block 15 into the grooves 14. These pins prevent the block 15 from tilting

longitudinally with respect to the beam. The block 15 is preferably substantially flush with the top and bottom of the adjacent portions of the beam and has mounted on its upper 60 face a seat 17 and handhold 18. The block 15 is of the same thickness as the spacer 12, while the spacer 13 is of less thickness. A bolt 19 extends through the beam at the spacer 13 and is provided with a wing-nut 20, 65 whereby the side bars 8 may be drawn together for clamping the block 15 in a desired position of adjustment along the beam. The spacers 12 form stops for limiting the outward adjustment of the seats. 70

The upper end of the post 5 is preferably capped with a metal ferrule 21. The cap 22, which forms the seat for the head of the post 21 within the beam, is formed of sheet metal bent to an inverted-U shape with horizontal 75 flanges 23 for securing the cap to the edges of the side bars 9 of the beam. The top of the cap 22 is indented at 24 near each end, as shown in the drawings, thus providing a seat for the head of the post and preventing said 80 head from slipping longitudinally within its socket, while at the same time permitting the desired longitudinal tilting of the beam. The width of the socket in the cap 22 is substan- tially the same as the diameter of the ferrule 85 21, so that the beam is prevented from tilting sidewise. A middle seat 25 is also provided to accommodate one or more persons upon that part of the beam.

The operation of the device shown is as fol- 90 lows: In erecting the device the board or plate 6 is laid upon the ground and the stake 5 is driven through the central aperture therein. The plate 6 is then securely pinned to the ground by the stakes 7. The beam is 95 then seated upon the top of the post. To adjust the seats 17, the wing-nut 20 is loosened, permitting the side bars 8 to spring apart and free the block 15. This block may then be slid to the desired position and locked in such 100 position by tightening the wing-nut 20.

What I claim as my invention, and desire to secure by Letter's Patent, is—

1. A seesaw and roundabout comprising 105 an upright, a beam balanced and rotatable on the top of said upright, said beam comprising a pair of side bars secured together and dis- posed on edge in parallel relation to each other, spacers separating said bars, a block mounted between said bars at each end of said beam, each of said blocks having thereon a 110 seat and being slidable longitudinally of the

beam and means for drawing the side bars toward each other for clamping the block in a fixed position.

2. A seesaw and roundabout comprising 5 an upright, a beam balanced and rotatable on the top of said upright, said beam comprising a pair of side bars secured together and disposed in parallel relation to each other, spacers separating said bars, a block mounted 10 between said bars at each end of said beam, each of said blocks having thereon a seat and being slideable longitudinally of the beam, and means for drawing the side bars toward each other for clamping the block in a 15 fixed position, said beams having longitudinal grooves in their opposed faces and said blocks having projections extending into said grooves to prevent said block from tilting with respect to the beam.
- 20 3. A seesaw and roundabout comprising an upright, a beam balanced and rotatable on the top of said upright, said beam comprising a pair of side bars secured together and disposed in parallel relation to each other, 25 spacers separating said bars, a block mounted between said bars at each end of said beam, each of said blocks having thereon a seat and being slideable longitudinally of the beam, a spacer at each end of the beam outside of said

movable block and forming a stop for limiting 30 the outward adjustment of said block, said spacer being of substantially the same thickness as said block, a second spacer inward of each end and being of greater thickness than said block, and a bolt extending through said 35 bars at a point between said spacers and adapted to draw said side bars together for clamping said block.

4. In a seesaw and roundabout, the combination of an upright post, a beam balanced 40 upon the top of said post and rotatable thereon, said beam having a central oblong aperture and a cap seated in said aperture for engaging the top of the post, said cap being bent to an inverted-U-shaped form having lateral 45 base-flanges for engaging the bottom face of the beam, the top of said U-shaped cap being indented at each end to form a central seat for the top of the post between said indentations, all arranged to permit said beam 50 to tilt longitudinally and to prevent said beam from tilting transversely.

Signed at Chicago this 9th day of October, 1905.

JOHN MUELLER.
